CLAIM

The ornamental design for a frost and ice scraper, as shown and described.

DESCRIPTION

FIG. 1 is a top plan view of a frost and ice scraper showing my new design;

FIG. 2 is a side elevational view thereof, the appearance being the same from both sides;

FIG. 3 is a bottom plan view thereof; and FIGS. 4 and 5 are left and right, respectively, end elevational views thereof.

FIG. 6 is an enlarged, perspective view as seen from the bottom, one end and one side.

FIG. 7 is an enlarged, perspective view as seen from the top, one end and one side.

FIG. 6

FIG. 7
